MILON J. TRUMBLE, OF ALHAMBRA, CALIFORNIA.

METHOD FOR OPERATING A BATTERY OF RETORTS.

Application filed February 1, 1926. Serial No. 85,132.

The general character of my present invention being indicated by the above title, I may state, at the outset, that this invention relates to the treatment of shale, or the like, in the general manner set forth in my pending application, Serial No. 648,366, filed June 28th, 1923, and somewhat more completely set forth in my subsequent application, Serial No. 751,865, filed November 24th, 1924.

This invention relates particularly to the treatment of shale with superheated steam, or the like, in separate retorts arranged for cyclical operation, one retort of a set being discharged and recharged at a time when another retort is undergoing a finishing operation, intermediate retorts being in intermediate conditions, or temperature phases, and a common vapor outlet being so provided and connected as continuously to receive all or a part of the recovered values; and it is an especial object of this invention, by dividing a complete set of retorts into subgroups, and providing suitable connections thereto, therebetween, and therefrom, to effect important economies in the use of superheated steam, or the like, in the recovery of hydrocarbon products from oil-bearing shales, lignites, or the like.

It is an object of this invention to provide shale treating equipment and methods in which subgroups of retorts, such as subgroups each comprising two or three or four retorts, may be very closely interconnected in various arrangements, each such subgroup being provided with a superheater, and the separate retorts and groups being so interconnected that any given quantity or charge of superheated steam, or the like, may pass, as from a steam boiler, first through a suitable superheater, then successively through the retorts of a single subgroup, not charged in immediate succession, then through another superheater, then through the retorts of another subgroup, finally issuing, with evolved and entrained values, into a vapor main,—said vapor main being connected, directly or indirectly (and with or without the interposition of power-generating means, as described in my prior applications) into a dephlegmator or into other means for the recovery of values therefrom.

It is a specific object of my invention to provide with a method wherein, using an organization of the general character re-

ferred to, and preferably interposing an oil catcher in advance of some or all of the mentioned superheaters, an entire series or set of retorts adapted for cyclical operation 60 may be interconnected in a great variety of alternative ways and so that any retort in the entire set may be the first to receive a given fresh charge of superheated steam, such steam passing successively through subsequent retorts in a unique and orderly manner, as hereinafter described, favorable to a conservation of heat.

It is an object of this invention to provide an improved method whereby a quantity of 70 steam introduced into any one retort of a complete set or battery of retorts may be economically utilized in obtaining values from all the retorts of the complete set, each quantity of steam being so heated and re-heated as at all times to remain above its boiling point, under the given conditions of operation.

The steam is preferably initially superheated to a preferred high temperature, carried through several retorts constituting a subgroup serially connected (but not consecutively charged) again superheated only after it has passed through all of said retorts constituting a subgroup, then carried 80 through another subgroup, similarly interconnected but as yet heated only to a lower temperature, then through another superheater, and so on,—the reheating of the steam being, in each case, preferably effected only after it has undergone a greater drop of temperature than that which has heretofore resulted from passing steam through a single retort, as used in the processes set forth in my above mentioned prior 90 applications. The steam is, as mentioned, kept at all times above the temperature at which condensation of water might occur, and, in preferred embodiments of this invention, in order to avoid "burning" or excessive 100 cracking of the vaporized or entrained hydrocarbon products, an oil catcher is preferably so interposed, in advance of each superheater, that said products shall be, in large part, removed from the advancing 105 steam, just before the latter enters the respective superheaters subsequent to an optional initial superheater.

It is a further object of this invention to provide a shale treating method or process 110 in which, a complete set of retorts being divided into like subgroups, the charging of a

first retort of a first subgroup is followed by a charging of the first retort of a second subgroup, then by the charging of a first retort of a third subgroup (if any) etc., including a charging of a first retort of the last subgroup. This is followed by the charging of a second retort in each subgroup, then by the charging of a third retort in each subgroup (if any) and by a charging of a fourth retort (if any) in each subgroup, etc., until all retorts are charged. The rise in temperature in the respective retorts being assumed to follow the indicated order of charging, the second retort of the first subgroup may (in the case assumed) accordingly be the fifth in the temperature series; the third retort in the first subgroup being then the ninth in the temperature series; and the quantity of steam introduced into any retort of any subgroup thus passes, after the system is in operation, successively through retorts whose mean temperatures are not consecutive, but are separated by intervals dependent upon the number of subgroups into which the entire set of retorts is divided.

It is, in brief, an object of my invention to provide means facilitating a changing of the interconnections between retorts arranged in subgroups and associated in the general manner above and hereinafter set forth, and so that each retort shall pass successively through a series of phases of the general character indicated in an accompanying diagram,—the highest temperature being employed in that retort which may be in its finishing phase (and into which a new quantity of steam is first introduced) and each newly charged retort being arranged initially to receive vapor-laden steam which has previously (but not consecutively) passed through earlier-charged retorts of the same set or battery and through interposed restorative means, for a partial removal of entrained hydrocarbons and/or a partial or complete restoration of temperature.

Other objects of my invention may be best appreciated from the following description of an illustrative embodiment thereof, taken in connection with the appended claims and the accompanying drawings, in which

Fig. 1 is a diagrammatic perspective view showing a complete set or battery of retorts as subdivided into four subgroups, with three retorts in each subgroup, parts being broken away.

Fig. 2 is a temperature diagram showing the general situation, as to temperature, in a battery such as is represented in Fig. 1, at the end of a cycle in which, all retorts of the battery having been successively charged (in the order in which their numbers appear in this figure) the first retort is in its

finishing phase. Figs. 1 and 2 are thus simultaneous, the former showing structural relationships and the latter showing thermal relationships; but the latter may be read also with reference to the cycle of any one retort. 70

Referring to the details of that specific embodiment of my invention illustrated in Fig. 1, retorts 1 to 12 inclusive being shown as comprising four subgroups (retorts 1, 2 and 3 being hereinafter referred to as constituting group A, retorts 4, 5 and 6 being hereinafter referred to as constituting group B, retorts 7, 8 and 9 being hereinafter referred to as constituting group C, and retorts 10, 11 and 12 being hereinafter referred to as constituting group D) 13 may be a steam line connected with any suitable source of supply, as a steam boiler suggested fragmentarily at 14; and the steam line 13 may be connected, as by separate valved branches 15^a, 15^b, 15^c and 15^d, with superheaters 16^a, 16^b, 16^c and 16^d,—each superheater being provided with a delivery pipe (as 17^a, 17^b, 17^c and 17^d) adapted to be placed alternatively in communication with any one of the retorts constituting a subgroup. 75 80 85 90

Parallel with the steam line 13, I show diagrammatically a vapor main or line 18,—which may be carried to a motor and dephlegmator 19 or to any other suitable apparatus for the utilization of its energy or the recovery of its values. Each of the respective retorts is provided with a valved inlet pipe 21-32 inclusive, the superheated steam delivery pipe 17^a, being shown as provided with valved branches 21^a, 22^a, and 23^a, leading respectively to inlet pipes 21, 22 and 23 of retorts 1, 2 and 3, the steam delivery pipe 17^b being provided with valve 105 branches 24^b, 25^b and 26^b leading respectively to inlet pipes 24, 25 and 26 of retorts 4, 5 and 6, the steam delivery pipe 17^c being provided with valved branches 27^c, 28^c and 29^c leading respectively to inlet pipes 27, 28 and 29 of retorts 7, 8 and 9, and the steam delivery pipe 17^d being provided with corresponding branches 30^d, 31^d and 32^d leading respectively to inlet pipes 30, 31 and 32 of retorts 10, 11 and 12. 110 115 120

In order that a charge of superheated steam introduced into any one of the described retorts may pass therefrom through the remaining retorts of the same subgroup, and from the last of these retorts either into one of the pipes 33^a, 33^b, 33^c or 33^d, leading toward the respective superheaters 16^b, 16^c, 16^d or 16^a (or, in the case of its delivery from a retort in its finishing phase, into the mentioned vapor line 18) I may provide the outlet pipes 41-52 inclusive, of the respective retorts with valved interconnecting returns 61-72, inclusive, and also with valved delivery branches 81-92, inclusive, leading into the vapor main 18, as 125 130

well as with valved interconnections 101-112 inclusive, leading into the various superheater pipes 33^a, 33^b, 33^c and 33^d.

In the use of apparatus of the general character described, the retorts constituting a set or battery, divided into subgroups in the general manner indicated, may be successively charged with an appropriate shale or other carbonaceous material capable of yielding hydrocarbon vapors; and, to simplify the reading of the accompanying drawings, I have shown those valves which might be simultaneously opened during the finishing phase of the treatment of a batch of shale, or the like, in retort 1 as disposed longitudinally of the pipes in which they are interposed; the remaining valves (shown in solid black) being transversely disposed.

In order to avoid subjecting all the hydrocarbons escaping from the respective retorts with the introduced steam repeatedly and unnecessarily to the high temperatures of the superheaters 16^a-16^d I may provide, at suitable points in the respective superheater feed pipes 33^a-33^d inclusive, oil catchers 113^a, 113^b, 113^c and 113^d; and, if desired, the respective subgroups (A, B, C, D) may be each surrounded by practically continuous insulation, somewhat as indicated by dotted lines 114 and 115,—only the route-controlling valves and the respective feed-openings and exit openings (not shown) of the respective retorts being exempt from or external to the mentioned insulation; and, if desired, in order that after the inlet ends (as, the upper ends) of the respective retorts are heated to a comparatively high temperature, steam may be admitted to the cooler parts (as, the central parts) of the respective retorts, some or all of the inlet pipes 21-31, inclusive, to the respective retorts may be provided with valved "shunting" feed pipes, such as are shown at 116.

Instead of charging the described retorts in the order of their consecutive numbering, assuming that a given quantity of superheated steam is to be passed through the retorts of one subgroup, then through an oil catcher and a superheater and into one of the retorts of a second subgroup (passing therefrom through another superheater, and continuing thus until delivered from a last retort of a last subgroup into the main 18, or its equivalent) it is essential, to the practice of my invention, that the mentioned retorts be successively charged and discharged in a sequence different from that of their consecutive numbering,—the charging of a first retort in a first subgroup being followed by the charging of a first retort in a second subgroup, then by the charging of a first retort in a third subgroup, etc. until one retort in each subgroup has been charged.

Thereafter, a second retort of the first sub-

group is charged, a second retort of the second subgroup, etc., continuing until a second retort in each of the subgroups has been charged. Thereafter a third retort (if there is such) is charged in each of the mentioned subgroups, this mode of charging being continued until all of the retorts are charged, the first retort of the first subgroup being then in its hottest or finishing phase, and the superheated steam admitted there, being passed through successive retorts in the manner indicated by the disposition of the valves shown in Fig. 1,—the steam and evolved and entrained and cracked and hydrogenated hydrocarbon products being finally delivered into the main 18 through the valved delivery branch 92, or its equivalent.

Thus, assuming a battery of 12 retorts to be divided into subgroups in the manner suggested above, the retorts having been charged in the following order,—1, 4, 7, 10; 2, 5, 8, 11; 3, 6, 9, 12, steam admitted to retort 1, in its finishing phase, may pass through the remaining retorts and the interposed superheaters (S) in the following sequence: 1, 2, 3; S, 4, 5, 6; S, 7, 8, 9; S, 10, 11, 12; and the thermal relationships then subsisting within the respective retorts may be substantially as indicated in Fig. 2.

That is to say, each of the retorts being in a different phase (assuming, for the sake of simplicity of explanation, that each finishing phase may be regarded as including a brief charging and discharging phase) the temperature within retort 1, to which a fresh quantity of steam is directly admitted from superheater 16^a (and presumably leaving the same at about 1100° F.) may, at the moment referred to, be about 850° F., the temperature in retort 4, in the next (eleventh) phase, being (in consequence of the reheating, within superheater 16^b, of steam passed through retorts 1, 2 and 3, but kept always above its condensing temperatures) in the neighborhood of (but presumably below) 800° F. As indicated in the figure referred to, retort 7 may, at this time, be in the 10th phase, retort 10 being in the 9th phase, whereas retorts 2, 5, 8 and 11 are respectively in the 8th, 7th, 6th and 5th phases, and retorts 3, 6, 9 and 12 are respectively in the 4th, 3rd, 2nd and 1st phases.

The curve constituting Fig. 2 not being a straight line, it will be appreciated that the rise in temperature within the respective retorts, after the charging thereof, is most rapid in the first and (especially) the concluding phases,—in which little energy is being used in the evolution of vapors; and it is an essential point of my present invention that a given quantity of steam, although preferably passing directly from one retort of a subgroup to another retort of the same subgroup, without appreciable intervening

loss of heat, does not pass from any retort directly into a retort in an adjacent phase,—as much as possible of the heat resulting from each superheating being utilized, for a 5 vaporizing or analogous effect, before the same is returned to a superheater or delivered into the main 18.

In the practice of my invention, the second superheating of each quantity of steam, even 10 though the temperature of the respective superheaters 16^a, 16^b, 16^c, and 16^d may be substantially the same, is not effective to produce, in the retort which it next enters, quite 15 so high a temperature as that in the retort (in a finishing phase) to which each quantity of steam is first introduced; and the respective quantities of oil collected by the oil catchers 113^a, 113^b, 113^c and 113^d, or their equivalents, may be expected to vary, from 20 time to time, according to the phases of operation of the retorts with which they are respectively connected; but it is obviously immaterial to the practice of my invention whether the oil caught in the mentioned oil 25 catchers (which may advantageously be kept at a temperature of about 350° F., more or less) are united with the values delivered through the main 18, or are otherwise disposed of.

30 In order to make perfectly clear the intended sequences of operation, in the use of a battery of twelve retorts subdivided in the indicated manner, I append a tabulation showing the courses followed by successive 35 fresh quantities of steam admitted, during the finishing phases of the respective retorts, assuming the adoption of the suggested order of charging:

Starting steam,

40 Into #1: S, 1, 2, 3; S, 4, 5, 6; S, 7, 8, 9; S, 10, 11, 12; (#1 finished);
Into #4: S, 4, 5, 6; S, 7, 8, 9; S, 10, 11, 12; S, 2, 3, 1; (#4 finished);
Into #7: S, 7, 8, 9; S, 10, 11, 12; S, 2, 3, 1; S, 5, 6, 4; (#7 finished);
Into #10: S, 10, 11, 12; S, 2, 3, 1; S, 5, 6, 4; S, 8, 9, 7; (#10 finished);
Into #2: S, 2, 3, 1; S, 5, 6, 4; S, 8, 9, 7; S, 11, 12, 10; (#2 finished);
45 Into #5: S, 5, 6, 4; S, 8, 9, 7; S, 11, 12, 10; S, 3, 1, 2; (#5 finished);
Into #8: S, 8, 9, 7; S, 11, 12, 10; S, 3, 1, 2; S, 6, 4, 5; (#8 finished);
Into #11: S, 11, 12, 10; S, 3, 1, 2; S, 6, 4, 5; S, 9, 7, 8; (#11 finished);
50 Into #3: S, 3, 1, 2; S, 6, 4, 5; S, 9, 7, 8; S, 12, 10, 11; (#3 finished);
Into #6: S, 6, 4, 5; S, 9, 7, 8; S, 12, 10, 11; S, 1, 2, 3; (#6 finished);
Into #9: S, 9, 7, 8; S, 12, 10, 11; S, 1, 2, 3; S, 4, 5, 6; (#9 finished);
Into #12: S, 12, 10, 11; S, 1, 2, 3; S, 4, 5, 6; S, 7, 8, 9; (#12 finished);

55 but it will be appreciated that a larger or smaller number of retorts may be comprised in a battery to which the principles of my invention are to be applied, and/or that a 60 battery consisting of twelve retorts (or of any preferred number of retorts) may be subdivided in various ways, provided that each subgroup always contains more than one retort and that a sequence of the general

character described is observed, and that the 65 steam is kept at all times above the temperature of condensation, under the conditions of pressure employed,—oil being preferably separated from the steam, in each case, before the same is admitted into a super- 70 heater.

Among the outstanding advantages of my described process are the following:

The shale introduced into the respective 75 retorts (preferably preheated in compartments, not shown, through or about which waste flue gases are advanced in the general manner made known in my prior applications) need be subdivided only to an extent sufficient to facilitate the handling 80 of the same; but it may be further subdivided, incidentally to its advance from the retorts toward the superheaters therebelow. Comminution of the hot shale is easily effected at this time, and is favorable to the 85 combustion of any residual "fixed" carbon,—which may amount to some 10%, more or less of the initial carbon content. About 90%, or more, of the kerogen originally present being obtainable in the form of oil, heat 90 conservation and high efficiency may be understood to be the outstanding advantages of the novel means and methods above outlined.

Although I have herein described a single 95 preferred embodiment of my invention, it should be understood not only that various features thereof may be independently used but also that numerous modifications might be made, by those skilled in the art to which 100 this case relates, without the slightest departure from the spirit and scope of this invention, as the same is indicated above and in the following claims.

I claim as my invention:

1. In the operation of a battery of retorts for the recovery of values from oil-bearing shales by the use of superheated steam, a 105 method which comprises: dividing said battery of retorts into subgroups each including more than one retort; providing each of said groups with a steam superheater; carrying a steam line having valved branches from a source of supply past said retorts; carrying a vapor main having valved branches also past said retorts; providing separate valved 110 communications leading to a common pipe from each of said groups to the associated superheater therefor; providing a superheated steam delivery pipe, extending from each of said superheaters, with valved branches leading to the respective inlets of the associated retorts; providing the outlet of each of said retorts with a plurality of valved connections additional to the mentioned valved communications with superheaters and leading respectively to said vapor main and to, another retort of the 115 120 125

same subgroup; charging the first retorts in all subgroups and then second retorts in all subgroups; so continuing; and passing each fresh quantity of steam successively through the retorts of one subgroup, through an oil catcher, through a superheater, and forward through the retorts of another subgroup, and finally into the said main.

2. In the operation of a battery of retorts for retorting materials which yield hydrocarbon oils when treating with superheated steam, a method which comprises: charging said retorts in such a sequence that, during regular operation, each retort is, at a given moment, in a different temperature phase; passing superheated steam through successively cooler retorts not in adjacent temperature phases until said steam approaches its temperature of condensation under the conditions of operation; then passing said steam, but without permitting it to condense, through an oil catcher and through a superheater and through additional retorts, not in adjacent temperature phases.— 25 the contents of these additional retorts be-

ing respectively cooler than the corresponding retorts first mentioned.

3. A method of operating a battery of retorts for recovering hydrocarbon values from oil-bearing materials which comprises: 30 subdividing said battery of retorts into like subgroups each including more than one retort provided with variable interconnections between the retorts of each subgroup; providing each subgroup with a superheater; 35 charging successively first retorts within all of said subgroups, then second retorts within said subgroups, so continuing until all retorts are charged; and passing steam through a superheater, then through the retorts of the first subgroup, then through an oil catcher and a superheater, then through the retorts of the second subgroup; and so continuing until the steam and associated hydrocarbon products are delivered from a 40 last retort of the last mentioned subgroups.

In testimony whereof, I have hereunto set my hand at Los Angeles, California, this 19th day of January, 1926.

MILON J. TRUMBLE.
